J. W. BRENKERT

VEHICLE DIRECTION AND STOP SIGNALING MEANS

Filed Dec. 31, 1923

FIG. 4.

FIG. 5.

FIG. 6.

Inventor
JOSEPH W. BRENKERT.

By *A. B. Bowman*

Attorney

UNITED STATES PATENT OFFICE.

JOSEPH W. BRENKERT, OF SAN DIEGO, CALIFORNIA.

VEHICLE DIRECTION AND STOP SIGNALING MEANS.

Application filed December 31, 1923. Serial No. 683,713.

To all whom it may concern:

Be it known that I, JOSEPH W. BRENKERT, a citizen of the United States, residing at San Diego, in the county of San Diego and State of California, have invented a certain new and useful Vehicle Direction and Stop Signaling Means, of which the following is a specification.

My invention relates to a vehicle direction and stop signaling means, and the objects of my invention are: First, to provide a signaling means of this class by which the direction of the signaling arm may be readily discerned at night; second, to provide an illuminating means in connection with a signaling arm whereby a long, narrow streak of light is directed outwardly to the side of the arm and extends in a direction longitudinally therewith; third, to provide a signaling arm which is adapted to be pivotally mounted on a vehicle and which is provided with an illuminating means for producing illumination on said arm in the general direction thereof; fourth, to provide a signaling arm which is provided with an elongated reflector which extends in the direction of the extended end of the signaling arm for illuminating a narrow portion of the side thereof; fifth, to provide a pivotally mounted signaling arm which is provided with a hollow portion and a slot in the side wall thereof through which rays of light are adapted to be directed; sixth, to provide as a whole a novelly constructed vehicle direction and stop signaling means, and seventh, to provide a means of this class which is very simple and economical of construction, durable, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a side view of my signaling

means supported on the side of a conventional windshield, showing certain parts and portions of the signaling means broken away and in section to facilitate the illustration, and also showing by dotted lines fragmentary portions of the signaling arm shifted to different positions; Fig. 2 is a top view thereof; Fig. 3 is a transverse sectional view taken through 3—3 of Fig. 1; Fig. 4 is a side view of a fragmentary portion of a slightly modified form of construction of my signaling means; Fig. 5 is a top view thereof, and Fig. 6 is a transverse sectional view thereof taken through 6—6 of Fig. 4.

Like characters of reference refer to similar parts and portions throughout the several views of the drawings.

The support 1, signaling arm 2, reflector and lamp supporting member 3, screws 4, socket member 5, insulating member 6, bulb 7, and the slotted tubular member 8, constitute the principal parts and portions of my signaling means in one form, as shown in Figs. 1, 2 and 3.

The signaling arm 2 of my signaling means is pivotally mounted near its one end on the support 1, which is secured to the windshield frame or any other portion of a vehicle body in any suitable manner. The signaling arm 2 may be of any shape or design, but is preferably provided with a hand with an extended index finger at its outer end. Intermediate the ends of the signaling arm and preferably near the pivotal end thereof is mounted the combined reflector and lamp guard and support 3, said arm being cut away at its middle portion to receive said member 3. The signaling arm 2 is preferably of thin construction and the member 3, mounted thereon, is preferably so positioned relatively thereto that a portion extends to either side thereof so that the bulb 7 positioned within the enlarged reflector portion 3^a of the member 3 is directed to both sides of the signaling arm. At the reduced portion 3^b of the member 3 are provided lugs 3^b, which are adapted to secure the member 3 to the arm 2 by means of the screws 4. Within the reduced portion 3^b of the member 3 is positioned the

95

100

socket member 5, which is insulated therefrom by the tubular insulating member 6 and in the one end of which is positioned the ruby colored bulb 7. The middle portion of the signaling arm 2, extending forwardly some distance from the member 3, is cut away for the reception of the tubular member 8. At the middle portion of the outwardly extending end of the member 8 is provided a slot 8^a, which is adapted to receive a portion of the signaling arm for positioning said member 8 laterally therein. The opposite end 8^b of the member 8 contiguous to the member 3 is slightly reduced and positioned within the open end of the reflector portion of the member 3, thus positioning the member 8 laterally relatively to the member 2 at its rear end. The member 8 is provided on each side with long, narrow slots 8^c through which the light from the bulb 7 is adapted to be directed. The portions of the tubular member 8 forming the upper sides of the slots 8^c are bent outwardly to prevent rain from coming therein, as shown best in Fig. 3. The walls of said member 8 also converge outwardly from the bulb 7 so as to intensify the light from the bulb at the outer end of the slot 8^c. The outer end of the tubular member 8 is preferably left open so as to partially illuminate the end of the hand at the extended end of the signaling arm and also so that rain or dirt blown into said member through the slots 8^c will be permitted to drop out when the signal arm is shifted to the downward position, as shown by dotted lines in Fig. 1 of the drawings.

In the modified form of construction of the signaling means, shown in Figs. 4, 5 and 6 of the drawings, the signaling arm consists of a bifurcated arm member 2, pivotally mounted in a support, and a pair of hand members 9, forming a hollow hand, which members are secured to the arm member 2 by means of screws 10. The portions of the hand members 9 which are secured to the arm member 2 are reduced and form a hollow portion for the reception of a socket member and bulb, which are also positioned in the bifurcated portion of the member 2. In the side walls of the hand members 9 are provided slots 9^a to permit the rays from the bulb, positioned in the reduced ends thereof, to be directed therethrough, as described in connection with the structure shown in Figs. 1, 2 and 3. The portions of the hand members 9 contiguous to the upper portion of the slots 9^a are also bent outwardly, as described in connection with the previous structure.

It is obvious from this construction, as illustrated in the drawings and disclosed in the foregoing specification, that there is provided a vehicle direction and stop signaling means as claimed at and set forth in

the objects of the invention, and though I have shown and described a particular construction, combination and arrangement of parts and portions and a certain modification thereof, I do not wish to be limited to this particular construction, combination and arrangement nor to the modification, but desire to include in the scope of my invention the construction, combination and arrangement substantially as set forth in the appended claims.

Having thus described my invention, what I claim as new and desire to secure by Letters Patent, is:

1. In a signaling means, a signaling arm, a hollow outwardly enlarging reflector provided with slits in its opposite side walls mounted centrally on said arm with its open end extended in the direction of the outer end of the said signaling arm, and a bulb positioned concentrically within said reflector and at the one end of the said slits. 80

2. In a signaling means, a signaling arm, a reflector member mounted on said arm with its open end extending in the direction of the outer end of said signaling arm, a bulb positioned concentrically within said reflector member and said signaling arm, and a separate extended hollow member supported by said signaling arm in front of the open end of said reflector member, said extended member being provided with a long narrow slot in its wall extending in the direction of said arm. 90

3. In a signaling means, a signaling arm, a reflector member mounted on said arm with its open end extending in the direction of the outer end of said signaling arm, a bulb positioned within said reflector member, and a separate tubular member positioned within said arm in front of the open end of said reflector member, said tubular member being provided at its front and back sides with long narrow slots. 100

4. In a vehicle direction and stop signaling means, a support, a signaling arm pivotally mounted near one end on said support, an outwardly enlarging combined reflector and bulb supporting member secured to said signaling arm near the center thereof, the reflector portion thereof being so positioned as to extend to either side of said signaling arm and the open portion thereof extending toward the outer end of said arm, and a bulb positioned concentrically within the reflector portion of said combined reflector and bulb supporting member. 110

5. In a vehicle direction and stop signaling means, a support, a signaling arm pivotally mounted near one end on said support, a combined reflector and bulb supporting member secured to said signaling arm, the reflector portion thereof being so positioned as to extend to either side of said signaling arm and the open portion thereof extending 120

toward the outer end of said arm, a bulb positioned within the reflector portion of said combined reflector and bulb supporting member, and an outwardly converging tubular member positioned in front of said reflector portion and provided with perforations in the side wall thereof extending sub-

stantially in the direction of said signaling arm

In testimony whereof, I have hereunto set 10
my hand at San Diego, California, this
22d day of December, 1923.

JOSEPH W. BRENKERT.
